2 Sheets-Sheet 2

UNITED STATES PATENT OFFICE

LAWRENCE MANNE, OF ROCKFORD, ILLINOIS

POWDER BLOWER

Application filed January 10, 1931. Serial No. 507,952.

This invention relates to improvements in powder distributing devices, and pertains particularly to an improved blower for insecticidal powders.

5 The primary object of the present invention is to provide an improved bellows operated powder blower or distributor having novel means for introducing air into the powder receptacle from which the powder 10 is ejected.

Another object of the invention is to provide a novel means for diffusing the air through the powder so that the powder will be expelled from the receptacle in the form 15 of a light dust.

Other objects and advantages of the present invention will become apparent as the description of the same proceeds, and the invention will be best understood from a consideration of the following detailed description taken in connection with the accompanying drawings forming part of this specification, with the understanding, however, that the invention is not confined to any strict 20 conformity with the showing of the drawings but may be changed or modified so long as such changes or modifications mark no material departure from the salient features of the invention as expressed in the appended 25 claims.

In the drawings:

Figure 1 is a view in side elevation of the blower embodying the present invention.

Figure 2 is an edge view of the same.

35 Figure 3 is a longitudinal sectional view taken on the line 3-3 of Figure 2.

Figure 4 is a sectional view taken on the line 4-4 of Figure 3.

Figure 5 is a sectional view taken on the 40 line 5-5 of Figure 4.

Figure 6 is a sectional view taken on the line 6-6 of Figure 3.

Referring more particularly to the drawings, wherein like numerals of reference indicate corresponding parts throughout the several views, the numeral 1 indicates generally the means provided for developing a blast of air for ejecting the insect powder from the blower receptacle, which means 45 constitutes a bellows which consists of the usual

two substantially heart shaped flat bodies 2 and 3 each of which is provided at its larger end with a handle 4. One of the handles carries a strap loop 5 which may be slipped over the other hand when the device is not in use to retain the bellows in compressed condition.

The sides 2 and 3 of the bellows are connected by the leather or other flexible body 6 and the side 2 has formed integral therewith a neck 7 along the inner face of which is formed the longitudinally extending groove 8. The portion 3 of the bellows which moves relative to the portion 2, which latter portion may be referred to as the fixed portion, has connection at its reduced end 9 with a separate neck portion 10, through the medium of a hinge 11. This neck portion 10 of the side of the bellows also has its inner face provided with a longitudinally extending groove 12 which coincides with the groove 8 to form an air passage 13 from the interior of the bellows to the powder receptacle, about to be described. The forward ends of the two neck portions 7 and 10 of the bellows sides are reduced as indicated at 14. The movable portion 3 of the bellows is normally maintained spaced from the fixed portion 2 by a spring 15 and this portion is also provided with an air inlet aperture 16 which is covered by a leather flap valve 17.

The neck of the bellows, which is made up of the portions 7 and 10, is connected with a powder receptacle which is indicated as a whole by the numeral 18, through the medium of the sleeve 19, one end of which receives the reduced portion 14 in the manner illustrated. The receptacle 18 is made up of the two portions 20 and 21 which are telescopically joined as illustrated, portions of the abutting faces of these portions being threaded as indicated at 22 to establish a tight connection therebetween.

The portion 20 of the receptacle, which may be referred to as the inner portion, has the sleeve 19 joined to the inner end wall 23 thereof as illustrated and extending laterally from the forward end of the sleeve 19 is an angularly shaped tube 24, the free end of one portion of which extends into the sleeve 19

and passes outwardly over the adjacent end 23 of the receptacle portion 20, while the other portion of the tube extends forwardly longitudinally of and against the side wall of the 5 portion 20 and tapers off to a point at its forward end as illustrated. The portions of the end and side walls of the inner receptacle portion 20, which are covered by the angular tube 24, are provided with apertures 25 so 10 that communication is established between the interior of the receptacle 18 and the sleeve 19 through these apertures and through the tube. It will be seen that when air is forced from the bellows into the sleeve 19 the apertures in the end wall 23 of the receptacle will 15 permit blasts of air to be directed forwardly and longitudinally through the receptacle, while the apertures through the side wall will introduce cross blasts of air so that a thorough agitation of the powdery contents of the 20 receptacle will be obtained.

The forward end of the removable portion 21 of the receptacle 18 is covered by an apertured wall 26 which serves as a baffle plate 25 and covering this apertured wall is a funnel shaped outlet 27 which empties into a short substantially cone shaped discharge nozzle 28, the base portion of which is provided with screw threads 29 for the purpose to be herein- 30 after described.

The short nozzle 28 which is integrally connected with the reduced forward end 27 of the receptacle may be employed for distributing powder over plants or other bodies which 35 are located close at hand. When the powder is to be distributed on objects which are some distance away from the user of the blower there is provided a long extension nozzle 30 which is of a diameter at one end to receive 40 the base portion of the nozzle 28 and which is interiorly threaded at this end for engagement with the threads 29. This has the short nozzle 28 inserted thereinto in the manner shown so that powder may be blown from the 45 receptacle therethrough onto vines or plants which would be out of reach when using the short nozzle 28.

From the foregoing description it will be readily seen that by the use of a powder 50 blower constructed in accordance with the present invention the air ejected from the bellows 1 will be introduced into the powder receptacle 18 in such a manner as to thoroughly whip up or agitate the powder and 55 this air also carries the powder with it in the form of a fine dust as it leaves the receptacle through the nozzle at the forward end thereof. In addition to this, by the addition of the apertured baffle plate 26 the powder is 60 again given a mixing or stirring before it leaves the receptacle so that any tendency for it to collect in a body before passing through the nozzle will be broken up. By the disposition of the entrance apertures in the manner 65 shown and described and by the employment

of the apertured baffle plate over the outlet of the receptacle, the powder is caused to leave the blower in a thoroughly dispersed condition or, in other words, in the form of a dust cloud rather than with the particles in 70 closely related formation as is the case with ordinary blowers.

It will also be seen that the receptacle may be easily and quickly filled by removing the outer section 21 from the end of the inner section 20, thus leaving the entire forward end of the inner section open so that the powder may be readily dumped thereinto. It will also be seen that the disposition of the air inlet apertures 25 to one side of the 75 longitudinal center of the receptacle has a further advantage in that the powder, when being dumped into the receptacle, will not be apt to pass into and fill the sleeve 19 as it would do if the apertures were located in the center of the bottom 23 over the forward end of the sleeve.

By tapering the longitudinally directed portion of the tube 24, from the rear to the forward end thereof in the manner shown, 80 the possibility of powder getting into the tube and clogging it is avoided and a much more effective transverse blast of air into the receptacle is obtained, for the thorough agitation of, and mixture of the air with, the 85 powder results.

Having thus described the invention, what I claim is:

1. A powder blower of the character described, comprising a receptacle, a discharge nozzle leading from said receptacle at one end thereof, an air receiving sleeve carried by the receptacle adjacent the other end, means for injecting air into said sleeve, and means for introducing the injected air into the receptacle from the sleeve through the end of the receptacle adjacent the sleeve and through the side wall of the receptacle.

2. A powder blower of the character described, comprising a powder receptacle, a discharge nozzle at one end of the receptacle, a tube having two connected portions with one extending over a portion of the other end of the receptacle and the other extending longitudinally of and along the side wall of the receptacle, said tube having communication with the interior of the receptacle through apertures in the adjacent walls, and means for forcibly injecting air into said tube for discharging it therefrom through the 115 apertured walls into the receptacle.

3. A powder distributor of the character described, comprising a powder receptacle, a discharge nozzle extending from one wall of the receptacle, an air tube formed of two 120 right angularly related portions, one of said portions overlying a part of the wall opposite the discharge nozzle and the other portion extending longitudinally of the receptacle along an adjacent side wall, said other 125

wall and said side wall having apertures therethrough opening into the air tube, the free end of the first mentioned portion of the air tube being open, a sleeve extending from 5 the said opposite wall of the receptacle and covering the open end of the tube, and means for creating an air blast and injecting the same into said sleeve.

4. A powder blower of the character described, comprising an elongated cylindrical receptacle formed in two sections telescopically connected, a discharge nozzle in communication with and extending from the outer end of one section, a sleeve member 15 carried by and extending from the outer end of the other section, a tube formed of two right angularly related portions and having one end of one portion extending into said sleeve with the said portion extending across 20 the adjacent end of the receptacle to the edge thereof, the other portion of the tube extending longitudinally along the side of the receptacle and having the free end thereof closed, said tube having communication with 25 the interior of the receptacle through apertures formed in the areas of the walls covered by the tube, and means connected with the sleeve and carrying the receptacle for creating an air blast.

30 5. A powder blower of the character described, comprising an elongated cylindrical receptacle formed in two sections telescopically connected, a discharge nozzle in communication with and extending from the outer end of one section, a sleeve member 35 carried by and extending from the outer end of the other section, a tube formed of two right angularly related portions and having one end of one portion extending into said 40 sleeve with the said portion extending across the adjacent end of the receptacle to the edge thereof, the other portion of the tube extending longitudinally along the side of the receptacle and having the free end thereof closed, 45 said tube having communication with the interior of the receptacle through apertures formed in the areas of the walls covered by the tube, means connected with the sleeve and carrying the receptacle for creating 50 an air blast, and an apertured plate in the portion of the receptacle carrying the discharge nozzle and covering the entrance to the nozzle.

6. A powder blower of the character described, comprising an elongated cylindrical receptacle formed in two sections telescopically connected, a discharge nozzle in communication with and extending from the outer end of one section, a sleeve member 55 carried by and extending from the outer end of the other section, a tube formed of two right angularly related portions and having one end of one portion extending into said sleeve with the said portion extending across 60 the adjacent end of the receptacle to the edge

thereof, the other portion of the tube extending longitudinally along the side of the receptacle and having the free end thereof closed, 70 said tube having communication with the interior of the receptacle through apertures formed in the areas of the walls covered by the tube, means connected with the sleeve and carrying the receptacle for creating an air blast, an elongated extension nozzle adapted to receive said first mentioned nozzle 75 in one end thereof, and means for threadedly connecting said nozzles together.

7. A powder blower of the character described, comprising a bellows having a neck 80 forming an outlet passage therefor, a powder receptacle, a collar receiving an end of said neck in one end thereof and having its other end joined with an end of the receptacle, an air tube having two right angularly related portions with one of said portions 85 extending radially of the end of the receptacle adjacent the neck and extending into said neck and the other portion of the tube extending longitudinally of and along the side of the receptacle, said other portion of 90 the tube tapering off to a point against the wall of the receptacle, said receptacle having the areas of the walls covered by the portions of said tube provided with apertures to establish communication between the collar and the receptacle through the tube, and a discharge nozzle leading from the opposite 95 end of said tube.

8. A powder blower of the character described, comprising a bellows having a neck 100 forming an outlet passage therefor, a powder receptacle, a collar receiving an end of said neck in one end thereof and having its other end joined with an end of the receptacle, an air tube having two right angularly 105 related portions with one of said portions extending radially of the end of the receptacle adjacent the neck and extending into said neck and the other portion of the tube extending longitudinally of and along the 110 side of the receptacle, said other portion of the tube tapering off to a point against the wall of the receptacle, said receptacle having the areas of the walls covered by the portions of said tube provided with apertures 115 to establish communication between the collar and the receptacle through the tube, a discharge nozzle leading from the opposite end of said tube, and an apertured baffle plate disposed transversely of the 120 receptacle over the discharge nozzle.

In testimony whereof I hereunto affix my signature.

LAWRENCE MANNE.
